US00D951614S

(12) United States Design Patent (10) Patent No.: US D951,614 S
Gibson (45) Date of Patent: * May 17, 2022

(54) SHOE

(71) Applicant: NIKE, Inc., Beaverton, OR (US)

(72) Inventor: Lee Gibson, Beaverton, OR (US)

(73) Assignee: NIKE, Inc., Beaverton, OR (US)

() Term: 15 Years

(21) Appl. No.: 29/787,899

(22) Filed: Jun. 9, 2021

(51) LOC (13) Cl. 02-04

(52) U.S. Cl. USPC ..... D2/947

(58) Field of Classification Search

(57) CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken lines depicting the remainder of the shoe form no part of the claimed design.

1 Claim, 3 Drawing Sheets
